UNITED STATES PATENT OFFICE.

EUGENE GUSY, OF BUFFALO, NEW YORK.

WINDOW.

1,370,890.

Specification of Letters Patent.

Patented Mar. 8, 1921.

Application filed June 17, 1918. Serial No. 240,384.

To all whom it may concern:

Be it known that I, EUGENE GUSY, a citizen of the United States, residing in Buffalo, in the county of Erie and State of New York, have invented new and useful Improvements in Windows, of which the following is a specification:

This invention relates more particularly to windows of that class in which the sash is provided with a guide-bar to which the same is pivoted so that it can be reversed for cleaning both sides and which is guided in a runway in the frame for ventilating in the ordinary way. This invention is however also applicable to windows in which the sash merely slides on the frame and is incapable of swinging relatively thereto.

It is the object of this invention to provide a window with improved means for producing a weather-tight joint between the sash and frame which is applicable to a pivoted sash, to a sliding sash and to one which slides and swings.

In the accompanying drawings:

Figure 1 is a fragmentary sectional elevation of a window equipped with one form of my improvement. Fig. 2 is an edge view of the sash shown in Fig. 1. Fig. 3 is a horizontal section, on an enlarged scale, taken on line 3—3, Fig. 1. Fig. 4 is a fragmentary sectional elevation of a window showing an embodiment of my invention which differs somewhat in detail from that shown in Figs. 1—3. Fig. 5 is a similar view showing an enlargement of the pivotal connection between the body and guide bar of the sash and adjacent parts. Fig. 6 is a horizontal section taken on the correspondingly numbered line in Fig. 5. Fig. 7 is a fragmentary sectional perspective view of the weather strip employed in connection with the construction shown in Figs. 4—6. Fig. 8 is a similar view showing the form of tension spring employed in connection with the construction shown in Figs. 4—5. Figs. 9, 10, and 11 are fragmentary horizontal sections, showing various modifications of my invention applied to different forms of windows.

Similar characters of reference refer to like parts throughout the several views.

Referring to the construction shown in Figs. 1—3, 1 represents the frame of the window which is provided in each of its upright stiles with a vertical channel runway or guideway 2 which may be of usual

construction and which has its channel or open side facing toward the adjacent upright edge of the sash. This sash in the present instance comprises a body 3 which may be of any suitable construction and has each of its upright edges terminating outside of the guideway or runway of the frame. Within the runway is arranged a guide bar 4 which in effect forms part of the sash and is capable of sliding vertically in this runway while raising and lowering the sash body for opening and closing the window so as to ventilate in the ordinary way, but the sash body is also capable of swinging vertically on this guide bar for the purpose of reversing the sash body and permitting either side of its transparent pane to be more conveniently cleaned from the inner side of the room. This guide bar is constructed of metal in the form of a channel in cross section and has its channel-sides facing the upright edge of the sash body while its convex side faces the back of the runway and is spaced apart therefrom. This guide bar is co-extensive with the upper edges of the sash body and its upper end may be connected by means of a cord 5 or similar means with a sash weight or spring such as are commonly employed in connection with sash for the purpose of balancing the weight of the sash.

The pivotal connection between the sash body and the guide bar may be variously constructed but that shown in the drawings is suitable and comprises a metal filling block 6 which is secured within the channel of the guide bar about midway of its length by means of soldering, brazing or otherwise and a pivot pin 7 having an inner screw threaded end which engages with the adjacent upright stile of the sash body and a cylindrical outer end which turns in a horizontal bearing opening 8, formed in the filling block. The web of the channel-bar is provided with an opening 9 through which the pivot pin passes and renders the latter accessible for assembling or dismembering the parts.

In order to produce a weather-tight joint between the sash and the frame for excluding rain, dust, and dirt, a weather strip is employed which is preferably constructed of sheet spring metal, such as spring brass, and this in the form shown in Figs. 1—3, comprises two corrugated, fluted or crimped side sections 10, 10 each of which is ar-

ranged between one of the lateral sides of the guide bar and the adjacent upright side wall of the runway of the frame, and a flat intermediate web 11 connecting the side sections and arranged between the opposing sides of the sash body and the guide bar. This weather strip is equal in length to the height of the guide bar and sash body and its opposite ends are flush therewith and its 5 central part is provided with an opening 12 through which the pivot pin 7 passes and causes the weather strip to move vertically with the sash body and guide bar. The corrugated side sections of this weather strip 10 are constantly under tension and exert a yielding pressure against the guide bar and the runway, thereby forming a weather tight joint between the guide bar and frame at all times which prevents the passage of 15 any dust, dirt or rain between these members. The weather strip and guide bar are also pressed constantly against the adjacent vertical edge of the sash body by means of one or more tension springs 13 preferably of 20 the leaf type, each of which is secured at one end to the web of the guide bar and bears at its opposite end loosely against this bar while its intermediate part is bowed and bears with its convex side against the back 25 of the runway, as clearly shown in Fig. 1. As the sash is raised and lowered the tension springs 13 slide up and down on the back of the runway and maintain the guide bar and the weather strip always in proper relation to the sash body, so as to form a 30 weather tight joint between these members.

The resilience of the weather strip and the tension springs permits them to adapt themselves to any expansion or contraction 40 of the runway due to changes in weather conditions and thereby forms a yielding joint between the sash and the frame which prevents the sash from binding in the frame and enables the sash to be moved freely up 45 and down on the frame without liability of binding as frequently occurs in windows of ordinary construction.

Furthermore, this yielding mounting of the sash on the window frame avoids any 50 looseness between these parts and prevents the same from rattling under wind pressure. Moreover, this construction is capable of being applied to windows now in general use without requiring any extensive alteration 55 or involving any considerable expense. The same is also low in cost, capable of being readily installed and can be operated by persons without any special experience.

In the construction shown in Figs. 4, 5, 6, 60 7 and 8 the guide bar 14 is constructed of wood, and is preferably made of inwardly or rearwardly tapering form in cross section and seated in a correspondingly shaped channel 16 on the adjacent central part of the weather strip. In this embodiment of

my invention the central section or web portion of the weather strip engages with a longitudinal locking groove 15 formed in the adjacent upright edge of the sash body 40 when the latter is in an upright position, 70 so that upon turning this sash out of its normal position this weather strip and sash bar will be pushed rearwardly toward the back of the runway 17 a distance equal to the depth of the locking groove in the sash body. During this turning movement of 75 the sash on the guide bar the same swings on a pivot pin 18 which passes through the web of this weather strip and has an inner screw threaded end engaging with the sash body and an outer plain end which turns in a bearing opening 19 in the sash bar. 80

For the purpose of more reliably connecting the weather strip with the wooden sash bar this strip is provided at intervals in its web with spurs or punch marks 20 which enter the wood of the guide bar and retain the same against longitudinal movement relatively to each other. The metal of the web of this weather strip may also be turned 90 inwardly in the form of a sleeve 21 which surrounds the cylindrical outer part of the pivot pin 18 and thereby increases the extent of the wearing surface of this pivotal connection. In the instance shown in Figs. 95 4, 5 and 6 the tension springs 22 are each constructed in the form of a leaf which is secured with its central part to the inner side of the guide bar and bears at its opposite ends against the back of the runway. 100

In the construction shown in Fig. 9, the guide bar 23 engages directly with the vertical edge of the sash body 41 and is pivotally connected therewith by means of a pivot pin 24 and the weather strip comprises two 105 corrugated or crimped side sections 25, 25 which are interposed between opposite sides of a rib 26 on the back of this guide bar and the adjacent side walls of the frame runway 27 and an intermediate flat web section 28 connects these side sections and bears against the back or inner sides of said rib. This web is provided midway of its length with an outwardly-turned sleeve 29 which surrounds the inner end of the pivot pin 24 and thereby interlocks the weather strip with the guide bar so as to compel the same to slide together, and also forms a bearing surface for the pivot pin. In this instance, the tension spring 30 is interposed 110 between the central section or web of the weather strip and the back of the runway. 115

If desired, my improvements may be modified so as to render the same applicable to windows in which the guiding portion 125 of the sash equivalent to the guide bar is formed integrally with the body of the sash and slides directly in the frame runway. Such instances are shown in Figs. 10 and 11 in each of which the sash body 31 is 130

provided at its upright vertical edge with a rib 32 which is spaced on its opposite lateral sides away from the upright walls of the runway 33 in the window frame.

- 5 In Fig. 10 the weather strip is constructed of spring sheet metal and comprises two corrugated or fluted side sections 34 each of which is arranged between one side of the sash rib 32 and the adjacent side wall of 10 the respective runway, and a central web section 35 connecting the side sections of this weather strip and interposed between the inner edge of the rib and the back of the runway. This web is compelled to move 15 vertically with the sash by forming punch marks or spurs 36 in this web which enter the wood of the sash. The side sections of the weather strip shown in Fig. 10 are composed of a plurality of plaits which 20 form six plies, the outmost one of which projects inwardly or toward the back of the runway but in Fig. 11 each of these corrugated side sections 37 of the weather strip comprises only three plies, the outermost 25 one of which projects outwardly or for-

wardly. The number of plies in each spring side section of the weather strip and the direction in which the last ply thereof terminates is however immaterial and is governed by the character of the window 20 which is being mounted and the space which is available for that purpose.

Each of the several forms of my invention permits of mounting windows so that they are weather proof and noiseless and 35 in a manner which is economical and does not detract from the general appearance of the window.

I claim as my invention:

A window comprising a frame having a 40 channel, a sash having an edge portion arranged in said channel, and a weather strip constructed of spring metal and comprising two corrugated side sections arranged on opposite sides of said edge portion and the 45 adjacent wall of said channel and an intermediate web section connecting said side sections.

EUGENE GUSY.
